UNITED STATES PATENT OFFICE.

DENNIS BUOY, OF LANCASTER, PENNSYLVANIA.

COUNTER-SCALE.

SPECIFICATION forming part of Letters Patent No. 277,878, dated May 22, 1883.

Application filed May 4, 1881. Renewed February 23, 1883. (No model.)

To all whom it may concern:

Be it known that I, DENNIS BUOY, a citizen of the United States, residing at Lancaster, in the county of Lancaster and State of Pennsylvania, have invented certain new and useful Improvements in Scale Beams and Weights; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to beams and weights especially designed for use with counter-scales, though capable of application to other kinds of balances.

The nature of said invention consists, chiefly, 20 in the combination, with a trough-shaped beam provided with slots or notches, or both, of a weight which has a shank that lies within said trough, and one or more projections or extensions adapted to set into said notches or slots.

25 It consists, further, in the combination, with the above, of one or more supplementary beams adapted to sustain a hanging weight or weights, and in certain peculiarities of construction hereinafter particularly set forth.

30 In the accompanying drawings, Figure 1 represents a perspective view of a counter-scale embodying my invention. Fig. 2 represents a plan view of the beam detached. Fig. 3 represents a detail perspective view of the detachable weight, and Fig. 4 represents a modification of the latter.

A designates the base of the scale; A', a bifurcated standard erected on one end thereof; B, the scale-beam, pivoted by gudgeons b 40 in the upper ends of said bifurcations; C, a detachable frame hung on pins or studs extending laterally from the short arm of said beam, and D a bowl or receptacle supported on said frame and detachable therefrom. The 45 scale-beam B is in the form of a trough with its hollow face upward. Its sides are provided at regular intervals with notches B', and its bottom is provided with openings B², also arranged at regular intervals. Either the notches 50 or the openings may, however, be dispensed with, though the former insure more delicate and reliable measurement.

E designates the weight which I employ, and which consists of a long heavy shank or body, E', which lies in the trough of the beam, 55 a neck, e, curved slightly upward, a head provided on the under side with a broad foreface wedge or point, E², and a handle, E³, for lifting and moving it.

In the modification shown in Fig. 4 the point 60 is dispensed with, and cylindrical laterally-extending studs or gudgeons E⁴ are used instead.

If the beam B is provided with openings B² and not with notches B', that form of weight 65 is used which has the point E². If the beam is provided with notches and not with openings, the weight is of the form shown in Fig. 4. In the former case the point sinks down into any one of the openings over which it is 70 brought, and holds the weight firmly in place by its wedge-like action. In the latter case the studs or gudgeons E⁴ sink into the corresponding notches, B', in the side flanges of the beam B. In either case the weighing is effected by taking hold of handle E³, lifting the head of the weight out of engagement with the beam, moving the said weight forward or backward far enough to just balance the commodity in the bowl or receptacle before mentioned, and then dropping the point or gudgeons into engagement with another hole or 75 pair of notches. The cylindrical shape of the studs or gudgeons E⁴ insures their being firmly seated in the notches. Other forms might be 80 substituted without departing from the spirit of my invention; but the results would be less perfect, as the studs would be in some danger of catching unduly on one side or the other 85 of the notches.

90 The weight can be lifted out of the beam at any time for inspection or cleaning of either device; but the long and heavy shank E', which nearly fills the interior of the trough, prevents accidental separation.

95 To allow greater delicacy in weighing, I attach to the side of the main beam above described a parallel supplementary beam, F, which is notched on its upper edge, and provided with a hanging weight, G. If the main beam weighs pounds, the supplementary beam may be used to weigh ounces. Of course other supplementary beams may be used for still greater delicacy of weighing, each beam being appro-

priately marked with figures in the usual manner. The other end of the beam is preferably provided with a sliding cap, H, which is slotted at h, and held to the beam adjustably by a screw, H', so as to afford a ready means of regulating the balance of the beam and compensate for changes of leverage due to increase or diminution of temperature or to any other cause.

10 Any suitable material may be used in the construction of these scales, and they may be made of any size desired.

I am aware that trough-shaped beams are not broadly new; also, that weights have been 15 set into the same. I do not broadly claim such construction and combination. My weight has a shank which extends longitudinally in the beam, parallel thereto, and said shank will hold it in place much more reliably than a mere 20 block or vertical shank extending down from the weight into the trough. Therefore,

Having thus fully described my invention, what I claim as new, and desire to secure by Letters Patent, is—

25 1. In combination with a trough-shaped

scale-beam, a detachable weight provided with a shank that extends longitudinally in said trough and parallel to said beam, substantially as and for the purpose set forth.

2. In combination with a trough-shaped 30 scale-beam having notches or openings, a weight having a shank that lies in said trough, and a head provided with a point or studs which set into said openings or notches, substantially as and for the purpose set forth.

3. In combination with a trough-shaped scale-beam having notches in its side flanges or walls, a weight provided with a shank which lies in said trough, a pair of cylindrical studs that set into said notches, and a handle whereby the head of the weight can be lifted and moved backward and forward in weighing, substantially as and for the purpose set forth.

In testimony whereof I affix my signature in presence of two witnesses.

DENNIS BUOY.
